UNITED STATES PATENT OFFICE.

JACOB PAYNE, OF BEATRICE, NEBRASKA.

REENFORCED-CONCRETE POLE.

1,420,571.

Specification of Letters Patent. Patented June 20, 1922.

Application filed May 13, 1921. Serial No. 469,199.

To all whom it may concern:

Be it known that I, JACOB PAYNE, a citizen of the United States, residing at Beatrice, in the county of Gage and State 5 of Nebraska, have invented a new and Improved Construction of Reenforced-Concrete Poles, of which the following is a specification.

My invention has reference to improvements in reenforced concrete structures and it is particularly designed to provide an improved reenforced cement pole that is especially adapted for telephone and telegraph service, and primarily my said invention has 10 for its purpose the provision of an improved pole of the character stated, of a relatively simple and economical construction, of light weight and maximum efficiency.

Another object of my invention is to provide a plastic pole structure in which the reinforcing elements include a central combined anchoring and reinforcing means, that is especially designed for the convenient and positive attachment of stay members and for 20 so supporting the entire reenforced or metallic structure of the pole that the said structure may be conveniently sustained within the mold box during the operation of pouring the cement.

In its complete make up my improved reenforced concrete pole embodies the peculiar features of construction and novel arrangement of parts, all of which will be fully explained in the following detailed 30 description of the structural portions thereof, specifically mentioned in the appended claims, and illustrated in the accompanying drawings, in which—

Figure 1 is a front view of a pole constructed in accordance with my invention.

Figure 2 is a perspective view of a portion of the pole, parts of the external or plastic body being omitted to better illustrate the metallic reenforced portion.

Figure 3 is a detail perspective view of a portion of the pole, and hereinafter referred to.

Figure 4 is a horizontal section of the pole taken through one of the eye clamp bolts that engage the T-shaped metal reinforce or core member.

Figure 5 is a view similar to Figure 4 taken practically along the line 5—5 of Figure 1.

Figure 6 is a diagrammatic cross section or wooden form in which the metallic struc-

ture of the pole is held while pouring the external or plastic body of the pole.

In the practical development of my invention, the body of the pole comprises a central core formed of a T-shaped metal member 10 which is of such length that it extends from end to end of the pole.

To the flat side 1 of the member 10 are secured (preferably at every six feet on the length of the pole) a series of flat steel cross reinforcing arms 2 and these are secured by rivets 3—3 that pass through the said cross arms and the opposite edges of the flat side 1 of the metal core or reinforcing member 10 as is best shown in Figure 5 by reference to which it will also be observed that at each of the cross members or arms 2 a supplemental member 20 is bolted to the angle flange 11 of the T-shaped member 10 that extends into the angle or rearwardly projected flange portion 40 of the concrete body 4 that is shaped into the desired form when pouring the concrete into a suitably prepared mold box, having a cross section 80 shape as is clearly shown in Figure 6 of the drawings.

When applying the outer or plastic body portion the upper end of the T-shaped central or metal core for a suitable distance is left exposed; that is, free of plastic covering, to provide for conveniently attaching the cross arms 8—8 that carry the telephone or telegraph wire insulators and which are attached by eye bolts 9 that take around 85 the T-shaped member 10 and are clamped to the said cross arms 8, through which the threaded ends of the said bolts pass and to which they are secured by the clamp nuts 6 as is clearly shown in Figure 4.

The several horizontal reinforcing members 2 are joined by longitudinally extending wires 15, two sets of such wires being provided for the flat face of the pole and a single set of such wires for the rib or 100 flange portion of the pole, as is best shown in Figure 2 of the drawings, by reference to which it will also be observed that the wires 15, as they pass from one of the cross members 2 to the next cross member 2 are 105 themselves crossed and twisted together, as at 25, and the said wires are passed over the flat side of the front cross member 2 and likewise across the supplemental arms 20 and laced through apertures 21—22 in 110 the said arms as shown.

16—16 designates supplemental reinforce

wires that extend straightway from the top to the bottom of the pole, and which are laced through apertures 21—22 in the outer and inner ends of all of the front cross arms 5 2, two straight reinforce wires 18—18 being extended along the outer and inner edge of the webb or flange 11, the said wires being laced through apertures 19—19 at the outer and inner ends of the supplemental or 10 laterally extended arm 20 as shown.

The cement pouring form indicated in Figure 6 may be of wood or steel and its shape makes it easy to place the fabricated reinforcement in place by simply hanging the 15 said reinforcement structures within the form.

Furthermore the arrangement of the form and the reinforcement structure makes it possible to keep the aforesaid reinforcement 20 always in sight during the pouring of the concrete thus making it easy to correct any misplacement thereof.

The box or form may be placed on benches or on the ground and the entire outer body 25 of the pole to be quickly poured of the wet mixture, thereby insuring the density and strength of the concrete without tamping or pressure and the proper time of setting the concrete may be finished by trowelling on one side only, which finishes the job.

To remove the form is is only necessary to turn it over and lift it off the completed pole, it then being ready for re-use.

At suitable places the form or mold box 35 is provided with fillers to produce the usual shape of step braces 30, see Figure 3.

When building my improved cement pole structure, for example a thirty foot pole as indicated in the drawings, the width of the 40 arms at the base is ten inches tapering to seven inches at the top, the small front arms being half as large as the wide arms to equalize proportion.

In my construction of cement pole the 45 same has been designed to develop a maximum of rigidity with the necessary amount of cement to thereby materially reduce the cost of the concrete poles.

From the foregoing description taken in 50 connection with the drawings, the complete construction, the manner of building my poles and the advantages of its use will be readily apparent of those familiar with the construction of and the handling of poles of 55 the type to which my invention relates.

What I claim is:

1. A pole comprising a cementitious body, a central T-shaped metal standard imbedded centrally of and extending lengthwise of the 60 said cementitious body, cross members secured to the flat face of the standard at intervals along its imbedded portions, other

members secured to the web or flange of the standard and projected at right angles to the cross members on the front face of 65 said standard and which are imbedded in the body portion, cross stay wires that extend from the top to the bottom of the body and interlacing with the cross members on the front of the T-shaped metal standard, 70 and other stay wires that extend from the top to the bottom of the body, the said other stay wires being disposed at right angles to the first mentioned stay wires, the said other stay wires interlacing the members attached 75 to the web of the standard and projected at right angles with respect to the front cross members.

2. A pole comprising a cementitious body, a central T-shaped metal standard 80 imbedded centrally of and extending the full length of the said cementitious body, cross members secured to the flat face of the standards at intervals along its imbedded portions, other members secured to the web 85 or flange of the standard and projected at right angles to the cross members on the front face of the said standard and which are imbedded in the body portion, stay wires that extend from the top to the bottom of 90 the body and are interlaced with the cross members attached to the front face of the T-shaped standard and other stay wires that extend from the top to the bottom of the body and interlacing the members attached 95 to the flange or web of the standard, and further stay wires that extend from the top to the bottom of the body and engage the outer ends of the members attached to the front and to the angled portions of the 100 standard.

3. A pole comprising a cementitious body of a substantially T-shaped metal standard imbedded centrally of and extending the full length of the cementitious body, cross members secured at intervals across the flat face of the T-shaped standard, other members attached to the web or T-shaped standard and projected at right angles to the front cross members, sets of stay wires that extend 105 the full length of the cementitious body which lace through the aforesaid front cross members, each of said sets of wires being twisted intermediate of each pair of cross members, like stay wires extending from the top to the bottom of the cementitious body and laced through the members attached to the flange of the T-shaped body, said wires being crossed and twisted at points intermediate of the standard, the said standard 110 being extended upwardly beyond the body and provided with means for attaching cross arms thereto.

JACOB PAYNE.
